UNITED STATES PATENT OFFICE.

MANDEL SPIEGLER, OF BROOKLYN, NEW YORK, ASSIGNOR OF ONE-FOURTH TO IRVING E. SPIEGLER AND ONE-FOURTH TO MAURICE KAUFMAN, BOTH OF BROOKLYN, NEW YORK, AND ONE-FOURTH TO JAKE FISHER, OF ROSE, NEW JERSEY.

NECKTIE.

Application filed November 18, 1920. Serial No. 424,958.

To all whom it may concern:

Be it known that I, MANDEL SPIEGLER, a citizen of the United States, and a resident of Brooklyn, in the county of Kings and 5 State of New York, have invented certain new and useful Improvements in Neckties, of which the following is a specification.

My present invention relates generally to neckties and more particularly to what are 10 generally known as four-in-hand ties, that type of tie which according to the usual construction embodies a relatively narrow central portion gradually widening toward its opposite ends and being substantially 15 wider at one end which is wrapped around the other end and finally passed through one of the turns to form the knot.

It is a well known fact that ties of this 20 nature when knotted and unknotted a few times become wrinkled, frayed and otherwise quickly lose their original appearance, and although it has been proposed to form a more or less solid permanent knot with a 25 guide opening through which one stiffened end of the tie may be passed, there is considerable objection to such an arrangement as the solidity and permanency of the knot precludes the appearance of a hand knotted tie.

According to my invention I propose the 30 advantages of the tie having a permanent knot, in respect to economy and at the same time preserve the advantages in appearance of the hand knotted tie.

It is quite obvious that the usual hand 35 knotted tie cannot be entirely removed without withdrawing the free end of the tie through the knot and it is equally obvious that with the usual tie such complete withdrawal prevents reinsertion of the free end 40 through the knot and requires that the knot be reformed in again placing the tie in proper position for wear.

It is my object to permit the free end of 45 the tie to be partially withdrawn through the knot and the collar encircling portion detached from the portion remaining through the knot by virtue of a detachable coupling which when reassembled can be pulled 50 through the knot and the tie once more placed in position with the original knot intact.

In the accompanying drawing which illustrates my invention and forms a part of this specification,

Figure 1 is a front elevation of my im- 55 proved necktie as it appears in use.

Figure 2 is a perspective view showing the position of the parts after removal of the tie,

Figure 3 is a detail section through the 60 coupling member,

Figure 4 is a perspective view of the coupling members detached.

Referring now to these figures my invention proposes a four-in-hand tie which may 65 be of the general shape of the four-in-hand ties now extensively used and comprising a central relatively narrow neck encircling portion 10 and the flowing gradually widening end portions 11 and 12 of which the latter, the 70 wider of the two is commonly used with two or more turns around the smaller flaring end 11 so that by passing the same downwardly through the last turn, the knot 13 of Figure 1 will be formed.

My invention proposes the insertion of a 75 detachable coupling generally indicated at 14, within the smaller flowing end 11 of the tie, in such position that when the tie is initially knotted, this coupling member 14 80 will be positioned below the knot as indicated in dotted lines in Figure 1 and concealed beneath the wider flowing end 12.

While capable of various constructions the detachable coupling 14 is preferably 85 constituted by a pair of cylindrical sections 15 and 16, each of which is tubular and is apertured adjacent to its outer end as at 17 in order that the adjacent portion of the necktie may be extended into such end and 90 secured as for instance by sewing, the stitches 18 passing through the apertures 17. Within its opposite end the section 15 has a rib 19, and within the opposite end of the section 16 is secured a projecting 95 head 20 adapted to be extended into the open end of the section 15, said head being flattened at one side as at 21 to permit its extremity to pass the rib 19 and having a slot 22 adapted to receive the rib upon partial rotation of the two sections 15 and 16 100 relatively to one another.

The necktie as proposed by my invention is made up in the first instance similar to the usual four-in-hand tie and is initially 105 tied by the purchaser in the usual way except that care must be taken that when tied and drawn tight the detachable connected

portions adjacent to the smaller of the two flowing ends of the tie will be below the knot and concealed beneath the larger of the two flowing ends.

5 In this way the knot assumes the form in the first instance desired by the individual, and this knot remains permanently in the tie thereafter in view of the fact that it becomes possible to partially withdraw the 10 flowing end of the tie through the knot until the coupling member 14 comes above the knot so that the neck encircling portion can be freed by disconnection at the coupling, leaving the smaller of the two flowing 15 ends of the tie with its section 15 of the coupling through the knot.

Thus when again placing the tie in position it is simply necessary to pass the neck encircling portion 10 around or through a 20 collar and re-engage the sections 15 and 16 of the coupling by inserting the head of section 16 into the open free end of section 15 and partially rotating the same. Then 25 the knot may be drawn into proper place in connection with the collar by pulling upon the smaller of the two flowing ends so as to again draw the coupling member downwardly through the knot.

My invention insures individuality of the 30 knot in spite of its permanency and effects great economy in use of the tie by virtue

of the fact that it eliminates reformation of the knot each time the tie is to be worn.

I claim:

1. A necktie in two sections having a detachable connector between the sections adapted to slide through a tie knot, said connector including a stud member and a socket member both of cylindrical form, the socket member having an internal cross rib 40 and the stud member having a socket entering head flattened at one side for movement past the rib and provided with a slot to receive the rib upon partial rotation of the stud member. 45

2. A necktie in two sections having a detachable connector between the sections adapted to slide through a tie knot, said connector including a stud member and a socket member both of cylindrical form, the 50 socket member having an internal cross rib and the stud member having a socket entering head flattened at one side for movement past the rib and provided with a slot to receive the rib upon partial rotation of the 55 stud member, said rib being spaced from one end of the socket and said stud member having a reduced portion at the inner end of said head, to interfit the end of the socket member as described.

MANDEL SPIEGLER.
